UNITED STATES PATENT OFFICE.

CHARLES WIEDNER, OF CIBOLO, TEXAS.

AUTOMATIC HEAT-REGULATOR FOR INCUBATORS.

1,373,282.

Specification of Letters Patent. Patented Mar. 29, 1921.

Application filed January 7, 1919. Serial No. 270,035.

To all whom it may concern:

Be it known that I, CHARLES WIEDNER, a citizen of the United States, residing at Cibolo, in the county of Guadalupe and State of Texas, have invented new and useful Improvements in Automatic Heat-Regulators for Incubators, of which the following is a specification.

It is the principal aim and object of the present invention to provide a device of the above mentioned character designed to be operably mounted within an incubator and on the heating lamp therefor and capable of being adjusted so as to insure of the extinguishing of the lamp when the temperature within the incubator casing reaches a predetermined point.

It is an additional and equally important object of this invention to provide a device of the above mentioned character wherein the thermostat carrying lever is operably connected with the wick extinguisher for extinguishing the flame of the lamp when the temperature reaches a predetermined point and for subsequently raising the damper of the lamp casing should the heat within the casing go above the predetermined point.

More particularly the present invention contemplates the provision of a device of the above mentioned character wherein the main actuating lever is mounted so that it will be moved downwardly by the diaphragm to consequently cause the successive actuation of the wick extinguishing carrying lever and the damper carrying lever, an operably mounted bell crank lever being arranged between the extinguisher carrying lever and the diaphragm carrying lever and between the damper carrying lever and the diaphragm carrying lever for insuring of the proper actuation of the parts at the desired time.

It is a more specific object of this invention to provide a device of the above mentioned character wherein a spring tensioned connection is provided between the extinguisher carrying lever and the bell crank lever for insuring the proper actuation of the wick extinguisher; to also construct the wick extinguisher of such size in relation to the lamp wick so that the extinguisher will leave a small portion near one end of the wick free to burn in order that such portion may act as a pilot for the lighting of the entire wick at the time the temperature

within the casing gets colder for the contracting of the diaphragm.

Other improvements and novel details in the construction and arrangement of the various parts of the apparatus will be brought out more in detail in the description to follow, which for a clear understanding of the invention should be considered in connection with the accompanying drawings forming a part hereof, and wherein is disclosed for the purpose of illustration a convenient and satisfactory embodiment of the invention. It is to be noted in this connection that minor changes in the construction and arrangement of parts may be made without departing from the principle of operation of the various parts.

The invention is clearly illustrated in the accompanying drawings, in which:

Fig. 1 is a front elevation of the invention applied to an incubator.

Fig. 2 is a top plan view thereof.

Fig. 3 is a side elevation of the invention the casing being shown in section.

Fig. 4 is a perspective detail of the thermostatic cracker carrying lever.

Fig. 5 is a detail of the extinguisher carrying lever.

Fig. 6 is a detail of the damper carrying lever.

Fig. 7 is a detail of the bell crank lever.

Fig. 8 is a detail view showing the extinguisher and its actuating parts in extended position.

Fig. 9 is a detail view showing the damper carrying lever raised, and

Fig. 10 is detail sectional view of the upper thermostatic crackers and shows the means by which they are suspended from their attendant bracket.

Similar characters of reference are employed in all of the above described views, to indicate corresponding parts.

Referring now, more particularly, to the accompanying drawings there is illustrated a portion of an incubator including a casing 1 to which is connected a bracket 2 on one side thereof for supporting a lamp 3 the heat of flames from the wick 4 of which are communicated to the heat drum 5 supported on the casing above the lamp. In this connection it is to be understood that the particular construction of the lamp and the drum form no essential part of the invention but are merely illustrating the ad-

vantages of the automatic heat regulator generally designated 6 which is operably connected to the casing, lamp and drum, the drum communicating with the casing 5 through the passage 12.

In reducing the present invention to practice a supporting plate 7 is connected to and arranged vertically on the drum 5 being formed at its upper end with an extension 8. 10 Also projecting from this casing or drum is an arm 9 which is arranged parallel to and in closely spaced relation with the plate 7.

In order to regulate the flame on the major portion of the wick 4 of the lamp a lever 10 is employed and has its upper end bent upon itself as at 11 while the bent portion 11 and the adjacent main portion are provided with opposed pairs of openings 13 and these portions are straddled about the arm 9 and 20 pivotally connected thereto by means of a pintle 12'. A flame dimmer 13' is now employed and consists of a relatively straight body of an inverted channel shaped configuration in cross section the inner end of which 25 is bifurcated leaving arms 14 which are pivotally connected in straddled relation about the lower end of the lever 10 by means of a pintle 15. The body of the member 13 is slidably supported on a tongue formed 30 integral with the chimney support 17 of the lamp and in the bottom of a recess 18 which is provided in the support. This tongue serves to guide the flame dimmer so that the body thereof will straddle the major portion 35 of the wick 4 when extended in a manner that will hereinafter become apparent. A bracket 19 is connected to the lower portion of the plate and forms a guide the ends of which serve as a means for limiting the swinging 40 movement of the lever 10. A spring member 20 is now employed for normally holding the flame dimmer and its lever in a retracted position and consists of a single piece of wire bent intermediate its ends to 45 provide a coil 21 and arms 22 which terminate in ribs 23 engageable with openings 24 in the lever and in the plate. With a view toward providing suitable means for imparting a swinging movement to the lever 10 50 a bell crank lever generally designated by the numeral 25 is employed and is pivoted on the pintle 12' and lies between the lever 10 and the plate. An ear 26 is formed on the vertical portion of the lever 25 at the 55 inner edge while through this ear is arranged a screw rod 27 the inner end of which terminates in an eye 28 swingably connected by means of a pintle 29 between the bent portion and the main portion of the lever 10. A coil spring 30 is arranged about the extended portion of the rod 27 and the rod is engaged by a knurled nut 31 which regulates the pressure of the spring 30 on the bell crank lever 25. By the arrangement of the ear 26 against the outer side

edge of the lever 10 near its upper end, it will be appreciated that when the spring 30 is properly adjusted on downward swinging of the bell crank lever the lever 10 will be swung to an extended position without 70 allowing independent swinging movement of the bell crank lever relative to the lever 10 for a purpose that will become apparent.

With a view toward providing suitable means for allowing the heat to escape 75 through the outlet at the top of the drum subsequent to the actuation of the flame dimmer the upper portion of the bell crank lever has its inner edge inclined as at 32 and its extreme terminal bent inwardly to form 80 a catch 33 designed for engagement with a knob 34 formed medially of the ends of a lever 35. This lever 35 is pivoted by means of a pintle 36 to the extension 8 at a point beneath the knob and has one portion twisted as at 36' while a damper 37 is connected centrally to the outer end of the twisted portion and normally arranged over the outlet of the drum. The counter-balancing weight 38 is formed on the opposite end of the lever 35. By this arrangement it will be appreciated that the spring 30 is regulated so that the catch 33 will not engage the knob until the lever 10 has been extended then on continued downward movement of the bell crank lever the catch will engage the knob so as to swing the lever 35 and raise the damper 37 from the outlet of the drum allowing the heat to escape therefrom. Suitable thermostatic means have been provided 90 for actuating the several levers and in reducing this feature of the invention to practice a bracket generally designated by the numeral 39 is employed being formed from a single piece of strap metal and bent into a 100 U-shaped configuration leaving an intermediate portion 40 and spaced arms at the terminals of which are formed the attached feet for flanges 42 which are anchored by suitable fasteners 43 to the top of the casing 110 1 interiorly thereof. A stud 44 is now employed and carries a pair of disk thermostatic crackers 45 the stud being inserted through the opening in the intermediate portion 40 of the bracket 39 and formed with 115 an annular groove 46 in which is removably fitted a spring clip 47 for removably supporting the crackers in a suspended position beneath the intermediate portion. An arm 48 continues from one of the feet 42 of the bracket and depends beneath the intermediate portion being parallel with one of the arms 41 of the bracket while swingably connected by means of a hinge 49 to the lower end of the arm 48 is a lever 50. The 120 inner portion of the lever is formed with an opening in which is fitted a stud 51 which carries at its upper end and above the lever a pair of thermostatic crackers 52 similar in construction to the crackers 45 and dis- 130

posed immediately beneath the crackers 45. The stud 51 alining the stud 44 is formed near its lower end with an annular groove in which is removably engaged a spring clip 5 52' for preventing accidental disengagement of the stud. The outer portion of the lever is bent into channel shaped configuration 53 and is movably arranged through a vertical slot 54 in the casing the outer end thereof 10 terminating in an eye 55 through which is arranged a threaded rod 56. The upper end of this rod is formed with a hook 57 for pivotally and detachably engaging with the outer end of the horizontal portion of the bell crank lever 25 while a knurled nut 58 is detachably connected to the lower portion of the rod and serves as a means for regulating the distance between the lever 50 and the bell crank lever 25.

20 In use, assuming that the spring 30 has been adjusted so that the lever 10 will move in an extended position before the catch on the bell crank lever strikes the stud, when the heat in the casing 1 goes above a predetermined temperature such as 102 Farenheit the crackers will expand to insure of the depressing of the lever 50 which owing to the connection of the rod 56 between the lever 50 and the bell crank lever, the latter 25 lever will be caused to swing about its pivot. Now by reason of the fact that the spring 30 is tensioned to cause the swinging of the lever 10 with the bell crank lever the said lever 10 will be swung into an extended position 30 against the tension of the spring member 20 so as to consequently slide the flame dimmer over the wick leaving only a part of the wick exposed and thus shutting off the transmission of heat to the drum. If 35 the temperature within the casing rises above 102 or 104 the crackers will expand still further assuring of a continued swinging of the bell crank lever so that the catch 33 will engage the knob 34 and raise the damper 37 from the outlet of the drum and 40 allow the heat to escape therefrom. Now when the temperature within the casing diminishes the crackers will contract allowing the bell crank lever to swing away from 45 the knob and this movement is assured by the spring 30 consequently permitting the damper 37 to close the outlet of the drum and, of course, the spring 20 assures of the return of the lever 10 and the removal of the 50 dimmer from the wick permitting the major portion to become again ignited so that the flames will act upon the drum. It is to be appreciated that that portion of the wick which is not covered by the dimmer serves 55 as a pilot for the relighting of the entire wick.

What is claimed as new is:

1. A device for the purpose indicated including in combination with an incubator 60 casing, a lamp and a drum receiving heat

from the lamp and connected with the casing and provided with a passage therethrough for the products of combustion, a damper closing the drum, a swingingly mounted bell crank lever, thermostatic means for operating said lever, a reciprocably mounted flame dimmer, operative connections between the bell crank lever and the damper and the flame dimmer, and resilient means interposed in said connections, whereby on the attainment of a specified temperature, the flame dimmer may be operated to dampen the flame and the damper of the drum simultaneously raised. 70

2. A device of the character described including in combination, a casing, a lamp and a heating drum connected to the casing above the lamp and provided with a passage therethrough for the products of combustion, a lever swingably connected to the drum, a flame dimmer operably connected to the lever and slidably mounted through the lamp, another lever swingably mounted on the drum, a damper carried by the last mentioned lever, a bell crank lever swingably connected to the drum, spring pressure means connected to the first mentioned lever and the bell crank lever and adjustable to insure the swinging of the first mentioned lever with the bell crank lever, co-operative means on the bell crank lever and the damper carrying lever for insuring the raising of the damper carrying lever upon movement of the bell crank lever subsequent to the predetermined extent, another lever operable swingably mounted in the casing and operably connected to the bell crank lever, and expansible and contractible means mounted in the casing and on the first mentioned lever for controlling the position of the said lever and consequently regulating the movement of the other levers. 100

3. A device of the character described including in combination, a casing, a lamp having a wick therein and a heating drum connected to the casing and positioned above the lamp and provided with a passage therethrough for the products of combustion, a plate carried by the drum, a lever swingably connected to the plate, a flame dimmer reciprocably connected to the lower end of the lever, means on the lamp for slidably supporting and guiding the flame dimmer, means on the plate for limiting the swinging movement of the lever to consequently regulate the movement of the dimmer, resilient means for normally holding the dimmer retracted, a bell crank lever swingably connected to the plate, spring pressure means between the first mentioned lever and the bell crank lever for insuring the movement of the first mentioned lever with the bell crank lever, a catch formed on one end of the bell crank lever, a damper disposed above the drum, a swingably mounted member con- 115 120 125 130

5 nected to the plate for carrying the lever, a knob on the last mentioned lever engageable by the catch for insuring the raising of the damper subsequent to the actuation of the
10 5 dimmer, a bracket within the casing, another lever swingably connected to the bracket and adjustably connected to the bell crank lever, and thermostatic crackers connected to the bracket and to the last mentioned lever for controlling the actuation of all of the levers.

15 4. A device of the character described including in combination a casing, a lamp, and a drum connected to the casing and disposed above the lamp and provided with a passage therethrough for the products of combustion, a swingably mounted lever, a flame dimmer connected to the lever and the lamp, a swingably mounted damper for the drum, a swingably mounted bell crank lever, manually adjustable spring pressure means between the first mentioned lever and the bell crank lever for insuring the movement of the first mentioned lever so as to actuate the flame dimmer, coöperative means between the bell
20 25 crank lever and the damper for raising the damper subsequent to the operation of the flame dimmer, and an operably mounted thermostatic cracker carrying lever within

the casing and operably connected to the bell crank lever for controlling the actuation of the flame dimmer and the damper.

5. A device of the character described including in combination, an incubator casing, a lamp having a wick, and a heating drum connected to the casing and disposed above the lamp and provided with a passage therethrough for the products of combustion, a 35 slidably mounted flame extinguisher for the wick, a swingably mounted damper arranged above the drum, a bracket within the casing, a lever swingably connected to the bracket, coöperative thermostatic crackers carried by the bracket and the lever for swinging the lever, means operably arranged between the flame dimmer and the damper for insuring 40 of the sliding of the dimmer preparatory to the raising of the damper, operable connection between said last mentioned means and the lever for insuring of the actuation of the parts, and resilient means for automatically 45 returning the parts to their former positions subsequent to the contraction of the thermostatic crackers.

In testimony whereof I affix my signature.

CHARLES WIEDNER.
